UNITED STATES PATENT OFFICE.

SIMON W. ROTHENBERGER, OF MINNEAPOLIS, MINNESOTA, ASSIGNEE OF ONE-FIFTH TO
FREDRICK E. COBB, ONE-FIFTH TO PHILLIP R. THOMAS, AND TWO-FIFTHS TO JAY W.
PIKE, ALL OF MINNEAPOLIS, MINNESOTA.

AIR-MOISTENER FOR INTERNAL-COMBUSTION ENGINES.

1,265,117.

Specification of Letters Patent. Patented May 7, 1918.

Application filed March 26, 1917. Serial No. 157,391.

To all whom it may concern:

Be it known that I, SIMON W. ROTHENBERGER, a citizen of the United States, residing at Minneapolis, in the county of 5 Hennepin and State of Minnesota, have invented certain new and useful Improvements in Air-Moisteners for Internal-Combustion Engines; and I do hereby declare the following to be a full, clear, and exact 10 description of the invention, such as will enable others skilled in the art to which it appertains to make and use the same.

My invention relates to air moisteners for internal combustion engines; and, to 15 this end, it consists of the novel devices and combinations of devices hereinafter described and defined in the claims.

In the accompanying drawings, which 20 illustrate the invention, like characters indicate like parts throughout the several views.

Referring to the drawings,

Figure 1 is a view in elevation illustrating the air moistener applied in working 25 position to the carburetor, intake manifold and exhaust manifold of an internal combustion engine;

Fig. 2 is a view of the air moistener in front elevation with some parts removed;

Fig. 3 is a view, principally in central 30 vertical section taken on the line 3—3 of Fig. 2;

Fig. 4 is a horizontal section taken on the line 4—4 of Fig. 1, on an enlarged scale;

Fig. 5 is a detail view, principally in section taken on the line 5—5 of Fig. 2;

Fig. 6 is an edge elevation of the vapor spraying nozzle;

Fig. 7 is a detail view in section taken on 40 the line 7—7 of Fig. 1; and

Fig. 8 is a view, principally in section illustrating a modified form of the vapor spraying nozzle.

The numeral 9 indicates as an entirety 45 a carburetor, of the standard or any desired construction, and the numeral 10 indicates a throttle control rod pivotally attached to the free end of an arm 11 on one of the trunnions 12 of the throttle valve of 50 said carburetor. The fuel intake manifold and the exhaust manifold of an internal combustion engine are indicated, respectively, by the numerals 13 and 14, and to

which fuel intake manifold is secured the carburetor 9.

The casing 15 of the air moistener comprises upper and lower castings detachably bolted together and having formed therein an air conduit 16. This air conduit 16, in the upper section of the casing 15, is expanded at its lower extremity to afford a valve seat 17. The lower extremity of the air conduit 16, in the lower section of the casing 15, is contracted to afford a restricted passageway 18, the purpose of 60 which will presently appear. Also formed in the lower section of the casing 15, is a water chamber 19 having an open front wall normally closed by a face plate 20 held in position by screws 21. A pliable packing 70 22 is interposed between the casing 15 and face plate 20 to afford a water-tight joint therebetween.

Air is drawn into the conduit 12 through a heater 23, under the suction stroke of the 75 engine, and which heater is attached to the casing 15 by a nipple 24 screwed into the receiving end of the air conduit 16. The heater 23 is provided with an air intake port 25, located at the opposite end thereof from 80 the nipple 24, and it is also provided with baffle plates 26 which retard the movement of the air therethrough from the port 25 to the nipple 24, and thereby increase the efficiency of the heater. The bottom of the 85 heater 23 is made concave in cross section to fit the exhaust manifold 14, is bolted thereto and receives its heat therefrom.

Water is supplied to the air moistener from a storage tank 27 through a pipe 28. 90 This storage water tank 27 is provided with a cap-equipped filling opening 29 and a drain valve 30, and is supported by brackets 31 above the heater 23 and from the exhaust manifold 14. The delivery end of 95 the pipe 28 is connected to the bottom of the casing 15 by a coupling 32, having a port 33 which connects said pipe with the water chamber 19. In the upper end of the port 33, is a valve seat 34. Water from the 100 chamber 19 is sprayed transversely into the restricted passageway 18 through a short pipe or nozzle 35.

Vapor is conveyed from the restricted passageway 18 through oppositely extended 105 pipes 36 to the arms of the fuel intake mani-

fold 13, and their intermediate portions are coiled at 37 around the exhaust pipe 14. The delivery ends of the pipes 36 are extended through the arms of the fuel intake manifold 13, close to the engine, and have secured thereto spraying nozzles 38. These spraying nozzles 38 are in the form of rings axially located, with respect to the adjacent portions of the arms of the fuel intake manifold 13, and they are circumferentially split to discharge both radially, inwardly and outwardly therefrom, a curtain of vapor transversely of said arms.

The air port 16 is normally closed by a valve 39 mounted on the seat 17 and arranged to be opened under the suction stroke of the engine. This valve 39 is provided with a stem 40, which works through a tapered cylindrical extension 41 integrally formed with the top section of the casing 15. The upper projecting end of the valve stem 40 is screw-threaded to receive a nut 42, which affords an adjustable abutment. Encircling the casing extension 41 and projecting end of the valve stem 40, is a helical spring 43 compressed between the top of the casing 15 and abutment 42 and yieldingly holds the valve 39 closed. By adjusting the abutment 42, the tension of the spring 43 may be varied, at will.

To prevent the valve 39 from opening under the suction stroke of the engine, when the air moistener is not in operation, and thereby disturb the setting of the carburetor 9, there is mounted in the air conduit 16 a normally closed choke or butterfly valve 44. This choke valve 44 is located between the valve 39 and restricted passageway 18 and is secured to an oscillatory shaft 45 mounted in the walls of the casing 15. Adjustably secured to the outer end of the shaft 45, is an arm 46 pivotally connected by a link 47 to a rigid radially projecting arm 48 on the throttle control rod 10. As the arm 48 is frictionally clamped by a draw bolt 49 on the rod 10, the same can be readily longitudinally adjusted on said rod.

The water supply port 33 is normally closed by a needle valve 50 mounted in the seat 34 with its body guided by a seat formed in a web 51 integrally formed with the casing 15 and extending into the water chamber 19. The needle valve 50 is yieldingly held closed by a coil spring 52, encircling the body of said valve, and compressed between the web 51 and an adjustable abutment 53, in the form of a pair of lock nuts, having screw-threaded engagement with the body of the needle valve 50. An arm 54, operated by a variable throw crank 55, on the shaft 45 is provided for simultaneously lifting the needle valve 50 from its seat 34 with the opening of the choke valve 44. This variable throw crank 55 comprises a disk-like head 56 secured to the inner end

of the shaft 45 and a crank pin 57, eccentrically located with respect to the axis of said shaft. As shown, the crank pin 57 is in the form of a set screw having screw-threaded engagement with a plate 58. This plate 58 has sliding dove-tailed engagement with a radially extended channel 59 formed in the face of the head 55. By reference to Fig. 5, it will be noted that the inner end of the crank pin 57 impinges against the head 55 and frictionally holds the plate 58 where set. Obviously, by adjusting the plate 58 in the channel 59, the throw of the crank may be varied, at will.

In some instances, it might be desirable to take the water supply for the air moistener from the circulating system of the engine, in place of the storage tank 27. In such a case, it would be necessary to interpose a suitable strainer in the pipe connecting the air moistener with the circulating system.

Referring to the modification shown in Fig. 8, the numeral 60 indicates an engine casing to which is directly bolted a carburetor 61. In this construction, the usual fuel intake manifold is entirely dispensed with, thereby making the form of spraying nozzle, shown in Figs. 6 and 7, impracticable. In this modification, as a substitute for the spraying nozzle 38, there is interposed, between the engine casing and carburetor, a spraying nozzle 62, having in its inner wall an annular slit, through which the vapor is discharged radially into the fuel intake, in the form of a curtain.

By reference to Fig. 2, it will be noted that the arm 54 is pivoted, at its upper end, to the crank pin 55 and its lower end is bent laterally under the abutment 53 and provided with an aperture, through which the body of a needle valve 50 is free to move endwise. It will thus be seen that the abutment 53 may be so set, with respect to the arm 54, as to permit the choke valve 44 to start to open before the needle valve 50 starts to open.

From the above description, it is evident that air drawn into the heater 23, through its intake port 25, under the suction stroke of the engine, is heated by the exhaust pipe 14. This hot air from the heater 23 enters the restricted passageway 18, has its movement accelerated thereby and, during the accelerated movement of the hot air, water is sprayed in a fine mist therein by the nozzle 35 and at substantially right angles thereto. The vapor, thus formed by the commingling of the hot air and water in the restricted passageway 18, is again heated, while passing around the exhaust manifold 14 in the coils 37 of the pipes 36. The fuel charge from the carburetor 9, in passing through and around the nozzles 38, is met by blasts of hot vapor at right angles to

the direction of the flow of said fuel charge. The meeting of the fuel charge and hot blasts of vapor produce a vortex at each nozzle 38 and thereby thoroughly commingles the vapor with the fuel charge. This commingling of the fuel charge and vapor also thoroughly vaporizes any particles of liquid gasoline in the fuel charge and any raw gasoline on the inner surface 5 of the intake manifold, due to condensation. It will thus be seen that the light hydrocarbon fuel charge and the vapor are thoroughly mixed before entering the explosion chamber of the engine, which results in perfect combustion, thus leaving no residue of carbon, and increasing the mileage by eliminating all waste of gasoline, prevalent in present-day carbureters. In case there is considerable carbon deposit in an engine, at the time 10 the air moistener is incorporated therein, the needle valve 50 may be adjusted to feed more water than would ordinarily be necessary to keep the engine free from carbon. After the carbon is removed from the engine, the needle valve 50 may be readjusted to feed just sufficient water to keep the engine free from carbon.

From the above description, it is also evident that the air and water valves of the 15 air moistener are automatically actuated by the throttle control for the carbureter. While the engine is running at low speed, the air and water valve of the air moistener are closed, so as to not interfere with the smooth running of the engine. As the 20 throttle control rod 10 is operated to open the throttle valve of the carbureter, with the increasing speed of the engine, the choke valve 44 and needle valve 50 are simultaneously opened, proportionately to the position of the throttle valve, to thereby admit the necessary amount of water and air for producing the required amount of vapor 25 for the fuel charge. By adjusting the variable throw crank 55, any desired amount of water may be admitted to the spraying nozzles 35. In adjusting the abutment 53, with respect to the arm 54, the needle valve 50 may be caused to open simultaneously

with the choke valve 44, or after the choke 30 valve 44 has started to open.

The above described invention, while comparatively simple and of relatively small cost to manufacture and install, is entirely automatic in its action and has, 55 in actual usage, proven highly efficient for the purpose had in view. It may be here stated, that, if the water supply for the air moistener gives out, air only need be used.

What I claim is:—

1. The combination with an internal combustion engine having a carbureter, of an air moistener arranged to deliver the vapor into the fuel intake of said engine and having air and water control valves, a connection for operating one of said valves from the throttle control of the carbureter, and an operating connection between said two valves.

2. The combination with an internal combustion engine having a carbureter, of an air moistener arranged to deliver the vapor into the fuel intake of said engine and having air and water control valves, a connection for operating the air valve from the 75 throttle control of the carbureter, and a variable throw crank connection between said two valves.

3. The combination with an internal combustion engine having a carbureter, of an 80 air moistener arranged to deliver the vapor into the fuel intake of said engine and having an air valve arranged to be opened by the suction stroke of the engine, said air moistener also having a choke valve and a 85 water-controlled valve, said choke valve being interposed between said air valve and fuel intake, a connection for operating the choke valve from the throttle control of the carbureter, and a variable throw crank connection 90 between the choke valve and the water-controlled valve.

In testimony whereof I affix my signature in presence of two witnesses.

SIMON W. ROTHENBERGER.
